UNITED STATES PATENT OFFICE.

CLEMENTS G. BELDEN, OF BALTIMORE, MARYLAND, ASSIGNOR TO THE CROWN CORK AND SEAL COMPANY OF BALTIMORE CITY, A CORPORATION OF MARYLAND.

BOTTLE-CAPPING APPARATUS.

1,397,617.

Specification of Letters Patent.

Patented Nov. 22, 1921.

Application filed April 5, 1919. Serial No. 287,711.

To all whom it may concern:

Be it known that I, CLEMENTS G. BELDEN, a citizen of the United States, residing at Baltimore and State of Maryland, have invented certain new and useful Improvements in Bottle-Capping Apparatus, fully described and represented in the following specification and the accompanying drawings, forming a part of the same.

10 This invention relates to bottle capping apparatus.

In such machines, of a recognized type, there is a bottle support and a capping head having relative movement and the stroke 15 of this relative movement is fixed. The throat device associated with the head is forced against the bottle with a predetermined pressure thereby to effect a seal and secure the cap to the bottle. As bottles of a 20 given trade size vary somewhat in height the predetermined capping pressure is ordinarily set for the shortest bottle and provision must be made for compensating for an over long bottle.

25 It is an object of the present invention to provide bottle capping apparatus such that the excess pressure is released substantially immediately upon the predetermined pressure being exceeded.

30 It is a further object of the invention to provide apparatus of the sort described capable of giving the maximum amount of compensation.

With these general objects in view, the 35 invention consists in the features, details of construction, and combination of parts which will first be described in connection with the accompanying drawing, and then more particularly pointed out.

40 In the drawing,—

Figure 1 is a view in vertical section of a portion of a bottle capping machine constructed in accordance with the invention; and

45 Fig. 2 is a similar view showing a different position of the parts.

Referring to the drawing, 11 represents a capping head having a housing 12 at one side thereof. Associated with the capping head is a throat device movable relatively thereto. Although capable of various constructions, as here shown, there is provided

a throat carrier 13 having a long sleeve portion 14 slidable in the capping head 11. The throat carrier is normally held in a lowered position, with respect to the head, by a spring 15 and this relative downward movement is limited by a nut 16 threaded into the head and engaged by a shoulder 17 on the sleeve. In the throat carrier is a frusto-conical throat ring or capping die 18. Associated with the capping head is a presser foot 19 slidable in an annular shoulder 20 formed on the interior of the sleeve 14, and in a sleeve 21 formed on a top nut 22. The presser foot is normally maintained in its lowered position by a spring 23 which bears against shoulder 20.

In the capping machine here illustrated the compensating mechanism is such as to cause the throat device to act as a unit with the head as long as predetermined capping pressure is not exceeded, and to permit the throat device to yield relatively to the head when such pressure is exceeded, thereby to relieve the bottle of the excess pressure.

This compensating mechanism includes a spring, a lever acted upon by this spring, a force transmitter associated with the lever, and a connector between the force transmitter and the throat device.

While the spring and its arrangement with respect to the lever may vary in construction, the present embodiment includes a coil spring 25 seated in a thimble 26 carried by the housing 12, and bearing against a collar 27 on a rod 28 slidable in a lug 29 formed on the housing.

As shown in the present embodiment, a lever 30 is pivotally mounted in the capping head on a pin 31. At its free end, this lever has a notch 32 with a hooked end 33 and this notch takes under a pin 34 on the collar 27. With this construction, it will be seen that the spring normally retains the lever in the position shown in Fig. 1 and that an upward force on the lever in excess of the spring pressure will cause the lever to swing upwardly, compressing the spring, as in Fig. 2.

The invention includes a force transmitter movable to make a shifting contact with the lever. This may, for example, be a second lever. Although capable of various con-

structions, as shown in the present embodiment, pivotally mounted in the housing 12 on a pin 36 is a lever 37. This lever is relatively short in comparison to the first lever 30 and it is so arranged with respect to the latter that in the normal position of the parts (Fig. 1) the free end of lever 37 is between pivot 36 and pivot 31 and the contacting portion of lever 37 is adjacent the 10 pivot of lever 30.

It will be seen that if lever 37 is swung upwardly from normal position its free end will make a shifting contact with lever 30. In order to prevent undue wear of the parts, 15 in the embodiment here shown, that portion of lever 37 which engages lever 30 is a rolling bearing 38 set in a suitable socket. It will be clear from the drawing that the lower edge of lever 30 is of a proper configuration 20 to always present a surface to be engaged by the rolling bearing 38. That is to say, lever 30 is formed with a cam surface, as at 39, to allow for the change in the relative position of the parts.

25 The invention includes a connector between the force transmitter and the throat device. Although capable of various constructions, as here shown, there is provided a link 40 having rounded ends 41, 42. The 30 end 41 is pivotally mounted in a socket formed in the lever 37 and end 42 is similarly mounted in a socket formed in a plate 43 carried by the sleeve 14.

If desired the rod 28 may be acted upon by 35 an auxiliary spring. As here shown, bearing against the underside of lug 29 is an auxiliary spring 44, the other end of which bears against a nut 45 threaded onto the lower end of rod 28. To inclose this end of 40 the rod and its spring, there is threaded into housing 12 a housing thimble 46.

Means is provided for adjusting the predetermined capping pressure. This may be accomplished, for example, by adjusting that 45 force of the spring which acts on the lever. As shown, thimble 26 which forms a seat for spring 25 is threaded into the housing 12. By adjusting the position of this thimble the force of spring 25 is varied as desired.

50 In describing the operation of the mechanism, spring 25 and the auxiliary spring 44 may be treated as one. Further, it may be assumed that the relative movement of capping head and bottle is obtained by elevating 55 the bottle to a stationary head.

As this movement takes place, the bottle neck enters the throat ring engaging and displacing the presser foot. As long as the 60 pressure between the bottle and the throat does not exceed predetermined capping pressure, as controlled by spring 25, the head and throat device act as a unit as the throat device is held down by the link, force transmitter, lever and spring. Should capping pressure 65 be exceeded, the force of the spring is

overcome. The pressure on the link causes the force transmitting lever 37 to swing upwardly in contact with lever 30, thus swinging the latter upwardly against the spring. By this movement of the parts the throat device yields and thus compensates for the 70 extra long bottle.

With the construction described, the leverage exerted by lever 30 on the force transmitter is relatively great when the parts are in 75 normal position, so that only a comparatively small spring is necessary to maintain capping pressure. At the same time, it is noted that, with the force transmitter making a shifting contact with lever 30, away 80 from its pivot, the leverage exerted rapidly diminishes so that the spring pressure is rapidly overcome and compensation is almost immediate.

The arrangement of levers and linkage 85 also makes possible a maximum amount of compensation.

Further, with the construction described, the maximum load on the spring when the lever is in its uppermost position is kept as 90 low as possible.

What is claimed is:

1. In a capping apparatus, the combination with a capping head, of a throat device carried by said head and movable relative thereto, a compensating spring, a lever acted upon by said spring, a force transmitter in engagement with said lever and movable to make a shifting contact along said lever, and a connector between said force transmitter and said throat device and having a pivotal relation with said elements.

2. In a capping apparatus, the combination with a capping head, of a throat device carried by said head and movable relative thereto, a compensating spring, a lever acted upon adjacent its free end by said spring, a force transmitter normally engaging said lever adjacent its fulcrum and movable to make a shifting contact along said lever, 110 and a connector between said force transmitter and said throat device and having a pivotal relation with said elements.

3. In a capping apparatus, the combination with a capping head, of a throat device carried by said head and movable relative thereto, a compensating spring, a lever acted upon by said spring, a movable force transmitter carrying a rolling bearing to make shifting contact along said lever, and a connector between said force transmitter and said throat device and having a pivotal relation with said elements.

4. In a capping apparatus, the combination with a capping head, of a throat device carried by said head and movable relative thereto, a spring, a lever acted upon adjacent its free end by said spring, a force transmitting lever substantially shorter in length than said first named lever and movable to 130

make shifting contact therewith, and a connecting link between said force transmitting lever and said throat device.

5. In a capping apparatus, the combination with a capping head, of a throat device carried by said head and movable relative thereto, a spring, a lever pivoted in said capping head and having its free end acted upon by said spring, a force transmitting lever substantially shorter in length than said first named lever, and pivoted in the capping head to have its free end normally engaging the first named lever adjacent its pivot and to be movable to make shifting contact with the first named lever in a direction away from said pivot, and a connecting link between the force transmitting lever and the throat device.

6. In a capping apparatus, the combination with a capping head, of a throat device carried by said head and movable relative thereto, a lever, a force transmitter acted upon by said lever, a connector between said force transmitter and the throat device and having a pivotal relation with said elements, and means for yieldingly holding said lever in normal position.

7. In a capping apparatus, the combination with a capping head, of a throat device carried by said head and movable relative thereto, a lever, yieldable means acting on said lever to hold the same in a normal position within the limits of a predetermined force, a force transmitter acted upon by said lever, and a connecting link between said force transmitter and the throat device.

8. In a capping apparatus, the combination with a capping head, of a throat device carried by said head and movable relative thereto, a lever, yieldable means acting on said lever to hold the same in a normal position within the limits of a predetermined force, a force transmitter acted upon by said lever and movable to make shifting contact

along said lever, and a connecting link between said force transmitter and the throat device.

9. In a capping apparatus, the combination with a capping head, of a throat device carried by said head and movable relative thereto, a compressing spring, a lever acted upon by said spring, a force transmitter normally acted upon by said lever with relatively great leverage and movable to make shifting contact along said lever to reduce the leverage exerted, and a connecting link between said force transmitter and the throat device.

10. In a capping apparatus, the combination with a capping head, of a throat device carried by said head and movable relative thereto, a compensating spring, a lever acted upon by said spring, a force transmitter in engagement with said lever and movable to make a shifting contact along said lever, and a connecting link in pivotal relation with said force transmitter and said throat device.

11. In a capping apparatus, the combination with a capping head, of a throat device carried by the head and movable relative thereto, a spring, a lever acted upon adjacent its free end by said spring and having a portion thereof formed with a cam surface, a force transmitting lever pivoted in the capping head to have its free end normally engaging the first named lever adjacent its pivot and to be movable to make shifting contact with said cam surface, and a connecting link between the force transmitting lever and the throat device.

In testimony whereof, I have hereunto set my hand.

CLEMENTS G. BELDEN.
